Des. 216,599
Patented Feb. 17, 1970

216,599

BEVERAGE SERVER OR THE LIKE

Arne Jacobsen, 403 Lyngbyvej, Gentofte, Denmark

Filed Sept. 30, 1968, Ser. No. 13,778

Term of patent 14 years

Int. Cl. D7—01

U.S. Cl. D44—21

FIG. 1.

FIG. 2.

FIGURE 1 is a perspective view of a beverage server or the like showing my new design, in the size and proportions of a coffee pot; and

FIGURE 2 is a side elevational view thereof, the opposite side being a mirror image; proportions of a tea pot.

I claim:

The ornamental design for beverage server or the like, as shown and described.
